DESIGN FOR A BRASSIÈRE

Joseph A. Coleman, New York, N. Y., assignor to Maiden Form Brassiere Company, Inc., New
York, N. Y., a corporation of New York

Application October 22, 1947, Serial No. 142,079

Term of patent 14 years

(Cl. D20—4)

To all whom it may concern:

Be it known that I, Joseph A. Coleman, a citizen of the United States, residing in the county of Bronx, city and State of New York, have invented a new, original, and ornamental Design for a Brassière, of which the following is a specification, reference being had to the accompanying drawings, forming part thereof.

Fig. 1 is a perspective view of a brassière, showing my new design with the shoulder straps broken away for convenience of illustration; and

Fig. 2 is a section taken on line 2—2 of the brassière shown in Fig. 1.

I claim:

The ornamental design for a brassière, as shown.

JOSEPH A. COLEMAN.
